YARN CONDITIONING PROCESS

Joseph B. Dickey, Rochester, N. Y., assignor to
 Eastman Kodak Company, Rochester, N. Y., a
 corporation of New Jersey

No Drawing. Application December 21, 1938,
 Serial No. 247,104

4 Claims. (Cl. 28—1)

This invention relates to the conditioning of textile yarns and more particularly to the conditioning of filaments and yarns composed of organic derivatives of cellulose such as cellulose acetate, cellulose propionate, cellulose acetate propionate, and cellulose acetate butyrate, to render them more amenable to textile operations such as knitting and the like.

As is well known in the manufacture of yarns, particularly those composed of or containing cellulose organic derivatives, it is necessary to treat the yarn in order to reduce the tendency toward breakage of the individual filaments or fibers when they are subjected to various mechanical strains and to lubricate the yarn in order to facilitate handling in such operations as spinning, twisting, winding and reeling. It is also necessary to treat yarn to adapt it for use as warp or filling or for the manufacture of various types of knitted fabrics. In knitting, it is particularly important that the yarn be soft and pliable in order that it may conform readily to the contour of the needles and thus produce a closely knit fabric free from such defects as "stitch distortion," "pin holes," "laddering," and the like.

Heretofore it has been proposed to employ softening agents such as polyhydric alcohols and similar agents as ingredients of yarn conditioning or lubricating formulas, generally in connection with mineral, animal or vegetable oils. It has been found, however, that most of the known lubricating agents and the various formulas containing them have certain drawbacks, one of the most serious of which is high vapor pressure, and in some cases too drastic a solvent action on the yarn. Many of such agents possess slight or insufficient lubricating power for the lubricants with which they are used, and it is accordingly necessary to employ blending agents or emulsifying agents in order to obtain operable yarn treating formulas. In addition, many of the known lubricating agents or insufficiently soluble in water to permit satisfactory removal by aqueous scour baths.

This invention has as its principal object to provide an entirely new class of yarn conditioning agents which are particularly adapted for the treatment of yarns composed of or containing organic derivatives of cellulose and capable of lubricating, deelectrifying and otherwise rendering such yarns more amenable to knitting and other textile operations. A further and specific object is to provide a class of conditioning agents which augment or assist the lubricating action of various lubricants when applied to such yarns.

A still further object is to provide yarn lubricating formulas which can be readily removed from the yarns by the usual scour baths. A still further object is to provide an improved method for the conditioning of yarns, particularly those composed of or containing organic derivatives of cellulose such as cellulose acetate, whereby the yarn is rendered capable of employment in a variety of textile operations where complicated designs or stitches are employed. Another object is to provide an improved type of yarn which is especially amenable to textile operations including circular knitting, weaving, spinning, and particularly in the manufacture of cut staple fiber and the like. Other objects will appear hereinafter.

These objects are accomplished by the following invention which, in its broader aspects, comprises the discovery that hydroxy alkane sulphonates and salts thereof derived from organic and inorganic bases and esters of hydroxy alkane sulphonates and salts derived from organic and inorganic bases. The hydroxy alkane sulphonates and their salts may be designated by the general formula:

25

The esters of hydroxy alkane sulphonates and their salts may be designated by the general formula:

30

(b is 1, 2, 3, 4, 5, and 6). In the above formulae X is a substituent selected from the group consisting of hydrogen and salt-forming radicals; b is 1, 2, etc.; R is a substituent selected from the group consisting of the substituted and unsubstituted alkyl and cycloalkyl groups, and R^1 is a substituent selected from the group consisting of the substituted and unsubstituted alkyl, alkylene, aryl, heterocyclic and cyclo alkyl groups, may be used as yarn conditioning agents and particularly as softening agents, with or without the addition of animal, mineral, or vegetable oils, in the treatment of yarns composed of or containing organic derivatives of cellulose. I have found that these compounds when employed as described in the detailed examples set forth below have a slight solvent and/or softening action on cellulose organic derivative yarns which renders such yarns soft and pliable without at the same time having too drastic an action thereon.

The intermediate necessary for the preparation of these compounds are prepared by treating alkylene oxides (ethylene, trimethylene, propyl-

35

40

45

50

55

ene, cyclohexylene, glycidol, styrene, epichlorohydrin,

5

with various hydroxulfide salts (sodium, potassium, ammonium, etc.) by methods previously described. Compounds of the type:

10

where X is ammonium, metal, etc., are formed. These compounds are then esterified by treating with organic acid anhydrides, chlorides, acids, etc. In addition I may prepare compounds of this type by treating halogenated alkyl sulfonates and their salts with salts of organic acids using known methods.

Examples of the preparation of typical compounds of this type are as follows:

20

PREPARATION OF ESTERS

Example 1

143 gm. sodium- β -hydroxyethane sulfonate having the formula

25

are placed in acetic acid and treated at 60° with 105 gm. acetic anhydride. Heating is continued for several hours and then the acetic acid is removed from the sodium- β -hydroxyethane sulfonate acetate having the formula

35

under reduced pressure. In a similar manner I may prepare the propionate, butyrate, valerate, laurate, oleate, stearate, etc.

Example 2

177 gm. potassium- β -hydroxypropane sulfonate having the formula

40

are dissolved in acetic acid and treated with 165 gm. methoxy acetic anhydride. The potassium- β -hydroxypropane methoxy acetate having the formula

50

is worked up as described in Example 1. In a similar manner there may be prepared the ethoxy acetate, benzyl oxyacetate, tetrahydrofuryloxyacetate, phenoxyacetate, cyclohexyloxy acetate, etc.

Example 3

200 gm.

60

(gamma-hydroxy-delta-hexane sulfonic acid ammonium salt)

65

are dissolved in acetic acid and treated with 550 gm. oleic anhydride as described in Example 1. The ester which is the oleate of gamma-hydroxy-delta-hexane sulfonic acid ammonium salt has the formula:

70

In a similar manner the crotonate, cinnamate, etc. may be prepared.

202 gm.

Example 4

(Sodium-2-hydroxycyclohexane sulfonate)

are dissolved in glacial acetic acid with 85 gm. sodium acetate and 136 gm. tetrahydrofuroyl chloride in acetic acid are added dropwise with stirring. The salt which is formed which is sodium-2-hydroxycyclohexane sulfonate tetrahydrofuroate having the formula

is filtered off and the reaction product is worked up as described in Example 1.

Example 5

14.2 gm. β - γ -dihydroxypropane sulfonate having the formula

are placed in an esterification apparatus with benzene, hexahydrobenzoic acid. The dihexahydrobenzoate having the formula

is formed by distilling off the water using p-toluene-sulfonic acid as a catalyst. In a similar manner there may be prepared the naphthenate abietate, succinate, etc.

In accordance with the invention these compounds may be applied directly to the yarn during or after spinning, or may be added to the spinning solution itself. I have found that these compounds have exceptional solvent powers which enable them to dissolve mineral oils and blown and unblown, drying and semi-drying, vegetable and animal oils and accordingly they may be, and preferably are, employed as ingredients of yarn conditioning or lubricating formulas in conjunction with agents which function wholly or partially as lubricants.

I have also found that the above mentioned compounds are particularly valuable as anti-static agents when applied to filaments, threads, fabrics, etc., composed of or containing organic derivatives of cellulose, such as cellulose acetate, cellulose propionate, cellulose acetate butyrate, and the like, and to textile materials in general.

In the following examples and description I have set forth several of the preferred embodiments of my invention, but they are included merely for purposes of illustration and not as a limitation thereof.

My invention will be more readily understood by reference to the following examples in which typical applications of the invention are set forth.

Example 19

5	Stearate pentane sulfonate	$\text{CH}_3-(\text{CH}_2)_2-\text{CH}-\text{CH}_2-\text{S}-\text{OH}$	Parts
		$\begin{array}{c} \text{OH} \\ \\ \text{O}=\text{S} \end{array}$	1
5		$\left(\text{CH}_3-(\text{CH}_2)_2-\text{CH}-\text{CH}_2-\text{S}-\text{OH} \right)$	
10	Oleic acid	$\text{O}-\text{C}-\text{C}_{17}\text{H}_{35}$	4
	Olive oil		5
			90

Example 20

15	Sodium sulfate	$\text{CH}_3-(\text{CH}_2)_2-\text{CH}-\text{CH}_2-\text{S}-\text{ONa}$	2
	Stearate of β -hydroxyethane sulfonate sodium salt	$\begin{array}{c} \\ \text{O}=\text{S} \end{array}$	15
		$\text{O}-\text{CO}-\text{C}_{17}\text{H}_{35}$	
20	Blown olive oil		80
	Sulfonated castor oil		10
	Oleic acid		5

Example 21

In a 20 percent acetone solution of cellulose acetate are dissolved 1-5% by weight of one or more of the compounds claimed in this application. The acetone solution is then extruded into an evaporative atmosphere and the filaments thus produced are wound or twisted and wound. If desired, the filaments produced by this process are oiled with any of the combinations of lubricants or lubricants plus conditioning agents previously described. Filaments thus prepared are of particular value in the preparation of cut staple fibers.

Any of the above compositions may be applied to the yarn intended for use in circular knitting by means of a bath, wick, spray, roller, pad or any suitable means. The amount of conditioning liquid applied may vary between 5-25% by weight of the yarn. Usually, however, the amount of conditioning liquid applied is about 10-15% by weight of the yarn. Yarn composed of cellulose acetate conditioned as described above gives excellent results when used in the circular knitting process.

As will be apparent from the above examples and description the conditioning agents of my invention may be applied by a wide variety of methods. For example, I may employ the agent as an ingredient of the spinning dope from which the filaments are formed, the amount of the agent so employed depending upon a number of factors, such as the particular cellulose derivative used in making the yarn, the solvent or solvent combination used in making up the spinning solution, and the degree of softness or pliability desired in the yarn, etc.

If the conditioning agent is to be applied to the yarn after spinning, this may be done by bringing the yarn in contact with a wick, roll, or felt wet therewith, or the liquid may be applied by immersion, spray, or otherwise. The particular point at which the liquid is applied may vary. It may, for example, be applied to the yarn inside or outside the spinning cabinet, between the guide and godet roll, between the godet or other roll or guide and the point of winding and/or twisting. In some cases, the liquid may even be applied to the yarn after winding onto cones, spools, bobbins, or the like or by the so-called "bobbin to bobbin" method. In the case of staple fiber manufacture, the liquid may be applied to the yarn prior to, or after, cutting into staple lengths.

The amount of the agent so employed will vary

widely depending upon the results desired, the specific nature of the material to which the agent is applied, the use to which the yarn is eventually to be put and other factors. For example, in a given case where a cellulose organic acid ester yarn such as a yarn composed of cellulose acetate, is intended for knitting, about 4 to 25% or more by weight, based on the weight of the dry yarn, may be satisfactory, while if the yarn is intended for weaving, the amount may vary between about 1 and 5%.

Although in the above examples I have referred primarily to yarn treating compositions containing only the conditioning agent and an oil, other ingredients such as solvents, non-solvents, emulsifying agents, blending agents and the like, may be added within the scope of my invention. Likewise, various dyes or other coloring matter may be included in case it is desired to permanently or fugitively tint or dye the material undergoing treatment.

Although I have found it convenient to illustrate my invention by reference to compositions containing specific percentages of the various ingredients, these percentages may vary widely depending upon the particular purpose for which the composition is intended. For example, if it is desired to control the solvent or softening action of the conditioning agent, the amount of the agent may be adjusted, as, for example, by reducing the amount of the agent and correspondingly increasing the amount of oil or other ingredient.

While I have described my invention with particular reference to the treatment of yarns composed of organic derivatives of cellulose such as cellulose acetate, the conditioning agents and formulas described herein are applicable to the conditioning of many other types of cellulose derivative yarns such as those composed of or containing cellulose propionate, cellulose butyrate, cellulose acetate propionate, cellulose acetate butyrate, ethyl cellulose, methyl cellulose, benzyl cellulose and others, as well as to the conditioning of silk, wool, cotton, viscose and other natural or artificial materials.

The term "yarn" as used herein and in the claims is to be understood as including a single filament, a plurality of filaments associated into the form of a thread, either of high or low twist, single or multiple threads associated or twisted together, composite threads composed of a mixture of natural and artificial filaments or a composite thread formed by twisting together individual strands of natural or artificial materials, as well as cut staple fibers produced from natural and/or artificial filaments or threads and spun yarn produced from such staple fibers.

As indicated above, the yarn conditioning agents of my invention are exceptionally good solvents for a wide variety of mineral, blown and unblown, drying and semi-drying animal and vegetable oils such as cottonseed, olive, castor, neatfoot, sperm and other oils. This enables them to be used with any of such oils in making up a variety of yarn treating formulas of varying composition.

The yarn conditioning method and compositions of my invention possess many outstanding advantages. The fundamental and outstanding characteristic of the agents employed in accordance with the invention is their ability to de-electrify yarns, especially those composed of or containing organic derivatives of cellulose such as cellulose acetate and render them amenable

to various textile operations, especially the manufacture of cut staple fiber. Another outstanding characteristic of these compounds is their exceptional solvent power for a wide variety of mineral, animal, and vegetable oils and their ability to act as lubricating assistants in conjunction with these oils when applied to such yarns. In addition, due to their solubility in water, they may be readily removed from yarns and fabrics by means of the usual aqueous scour baths. By employing the yarn conditioning agents and method of my invention as herein described, one is enabled to obtain highly satisfactory results in the manufacture of yarns and woven fabrics and especially the production from these yarns of closely knit fabrics free from defects such as pin holes, stitch distortion, laddering and the like.

What I claim is:

1. The process of conditioning yarn composed of or containing organic derivatives of cellulose to render it amenable to textile operations, including knitting, weaving, spinning, and the manufacture and use of staple fibers, which comprises applying to the yarn a lubricating and anti-static composition containing as its essential lubricating and anti-static component a compound selected from the group consisting of the hydroxy alkane sulfonates and the salts thereof derived from organic and inorganic bases and the esters thereof.

2. The process of conditioning yarn composed of or containing cellulose acetate to render it amenable to textile operations, including knitting, weaving, spinning, and the manufacture and use of staple fibers, which comprises applying to the yarn a lubricating and anti-static composition containing as its essential lubricating and anti-static component a compound selected from the group consisting of the hydroxy alkane sulfonates and the salts thereof derived from organic and inorganic bases and the esters thereof.

3. Textile yarns composed of or containing organic derivatives of cellulose, amenable to textile operations, including knitting, weaving, spinning, and the manufacture of staple fibers, said yarns being impregnated with a lubricating and anti-static agent comprising a compound selected from the group consisting of the hydroxy alkane sulfonates and the salts thereof derived from organic and inorganic bases and the esters thereof.

4. Textile yarns composed of or containing cellulose acetate amenable to textile operations, including knitting, weaving, spinning, and the manufacture of staple fibers, said yarns being impregnated with a lubricating and anti-static agent comprising a compound selected from the group consisting of the hydroxy alkane sulfonates and the salts thereof derived from organic and inorganic bases and the esters thereof.

JOSEPH B. DICKEY.
